[57] CLAIM

The ornamental design for a nail set, as shown and described.

DESCRIPTION

FIG. 1 is a perspective view of a nail set showing my new design;

FIG. 2 is a side elevational view thereof, the opposite side view being identical;

FIG. 3 is a side elevational view thereof rotated 45° from the position of FIG. 2, the opposite side view being identical; FIG. 4 is a side elevational view thereof rotated an additional 45° from the position of FIG. 3, the opposite side view being identical;

FIG. 5 is a top plan view thereof; and,

FIG. 6 is a bottom view thereof.

The broken line showing of the tip portion of the nail set in FIGS. 1-4 and 6 is for illustrative purposes only and forms no part of the claimed design.
